DESIGN FOR AN IRONING MACHINE CABINET

George W. Walker, Detroit, Mich., assignor to
The Apex Electrical Manufacturing Company,
Cleveland, Ohio, a corporation of Ohio

Application April 10, 1935, Serial No. 56,290

Term of patent 14 years

To all whom it may concern:

Be it known that I, George W. Walker, a citizen of the United States of America and a resident of Detroit, in the county of Wayne and State of Michigan, have invented a new, original, and ornamental Design for Ironing Machine Cabinet, of which the following is a specification, reference being had to the accompanying drawing, forming part thereof.

The Figures 1 and 2 are perspective views of

an ironing machine cabinet showing my design in which Figure 1 shows the cabinet in closed position and Figure 2 shows the cabinet in open position.

I claim:

The ornamental design for an ironing machine cabinet as shown.

In witness whereof, I have hereunto set my hand this 5th day of April, 1935.

GEORGE W. WALKER.
